12 Claims.

(Cl. 250—27)

My invention relates to improvements in the operation of electrical and electronic apparatus, and more particularly to means in combination therewith for operating such apparatus upon either direct or alternate current, and provides means for operation on direct current irrespective of the position of the plug connecting the power supply. Means are also provided for full wave rectification on alternating current circuits in apparatus susceptible of use on alternating or direct current. Means may be included in the device for efficiently operating standard lower voltage tubes on higher voltage power supply circuits, as well as means for stepping up the power supply voltage.

While one object of this invention is to provide a novel type of electronic and radio circuit which can be operated interchangeably from any alternating current or direct current source, another important object of the invention is to provide a novel form of amplifying circuit in which exactly the same circuit is used with alternating as with direct current, there being no switches necessary to change from one current to another as is common in devices intended for use with either alternating or direct current. Another important object is to provide a form of amplifying circuit which will give full wave rectification when used on an alternating current source, and can be operated from any direct current source regardless of polarity. Heretofore in circuits of this nature when operating from a direct current source, it has been necessary to reverse the plug, if it be so inserted that polarity is incorrect. In this circuit, however, it is impossible to insert the plug incorrectly inasmuch as polarity does not effect the operation.

In a device embodying the invention, a unidirectional current of positive polarity is impressed upon a filter and an amplifying unit in a radio circuit or other translating device, by means of a rectifying unit having a substantially constant impedance ensuring a continuing constant potential in the current being delivered.

By using electronic rectifying tubes, alone or in conjunction with resistors or condensers, it is possible to not only control the direction of flow of the current, irrespective of the polarity at the source, but to ensure the delivery to the translating device of current of positive polarity, the potential of which is subject only to variations in the potential of the current delivered at the source. Hence, the current impressed upon the translating device circuit will be substantially constant in relation to the line potential.

By the use of agencies such as are employed in a device embodying the invention, it is possible to produce a device which is so compact and has so little weight that it may be readily incorporated in the chassis of even a small radio set, hearing device or other type of translating device, and which, after installation, will require no attention in order to maintain the efficiency of the device.

10 In the accompanying drawings, I have illustrated various embodiments of the invention adapting it for use under different conditions.

Referring to the drawings,

Fig. 1 is a diagram of a device in which the rectifying unit is composed solely of electronic rectifying tubes;

Fig. 2 is a diagram showing a rectifying unit composed of a combination of resistors and an electronic rectifying tube, and in which the full potential of the line from the source is impressed upon the heater for this tube while the voltage of the current delivered to the filter is reduced;

Fig. 3 is a diagram showing an arrangement similar to that of Fig. 2, in which the heater current is of the same voltage as that delivered to the rectifier, in which, like in Fig. 2, the return is by a ground connection;

Fig. 4 is a diagram similar to that shown in Fig. 2, in which a direct metallic return line is employed, an electronic rectifying tube is used in each return line, and a condenser is used to increase the voltage of the current delivered to the filter;

Fig. 5 is a diagram showing the employment of a full metallic circuit for use with an alternating current source supply and a ground connection for use with a direct current source, the electronic rectifying tubes being between the source and the filter instead of in the return line, and in which condensers are used in lieu of resistors; and

Fig. 6 is a diagram showing an arrangement similar to that shown in Fig. 4, but omitting the condenser for raising the voltage impressed upon the filter.

It will be seen that each embodiment of the invention illustrated in the accompanying drawings has, in common with all other embodiments, a rectifying unit adapted to receive current from a source, and which embodies one or more electronic rectifying tubes so arranged in relation to each other, or so combined with resistors or condensers as to have substantially constant impedance and thus impress upon a filter a unidirectional current of positive polarity and of a

potential substantially constant with relation to the line potential, irrespective of the polarity of the terminals of the source with which the device is connected, and whether this source has a direct or an alternating current. Furthermore, each of these devices embodies a rectifying unit connected with the source by two branch lines, thus affording two constantly closed paths for the current flow, both of which are utilized with an alternating current source, and either of which may be utilized according to the polarity of the connection with the terminals of a direct current source.

It will also be noted that in each of the embodiments illustrated, the arrangement of the rectifying unit in relation to the filter is such as to eliminate substantially all hum from an alternating current, or from those pulsations commonly present in a direct current.

Each embodiment of the invention illustrated provides for two or full wave rectification.

Referring to Fig. 1 of the drawings, the rectifying unit has two branch lines 4 and 14 adapted to be connected with a source of either alternating or direct current by means of a conventional plug having terminals 2 and 3. Both branch lines discharge into a rectifying unit, and the output of this unit is connected by a line 18 with a filter consisting of an inductance 19 and condensers 62 and 63.

The rectified and filtered current is delivered through the line 45 to a translating device including the member 29 and the circuit of a radio receiving set which will be later described in detail. The return line of this receiving set, including the wires 25 and 26, is connected with a rectifying unit, and through said unit with both of the branch lines 4 and 14.

The rectifying unit proper contains a rectifying tube having an anode 16 and a cathode 17 between the branch line 4 and the filter, and a rectifying tube having an anode 28 and a cathode 29 between the return line 25 and the branch line 14, the anode 28 being connected with the return line 25 by the conductor 27.

The rectifying unit also contains an anode 57 and a cathode 58, the former of which is connected with the branch line 14 through the line 56, and the latter of which is connected through the line 59 with the line 18 through which current is impressed upon the filter as to one rectifying tube, and an anode 61 connected through the line 60 with the return line 25 and a cathode 15 connected with the branch line 4.

Heating elements 6 and 8 are provided in each tube, current being supplied thereto and to the tubes of the set through a branch line containing therein a resistance 5. The heater 6 is connected with the heater 8 through the lead 7, and the set tubes 10 and 12 are connected in series with the heaters of the rectifying tubes through the leads 9 and 11 and the circuit completed through the return line 13 connected with the branch line 14. The various heaters are connected in series, being energized by current flowing directly from the source, whether this be alternating or direct current. Across the return line 25 and the return line 13 of the heater circuit is a condenser 55.

The condenser 55 arranged in the shunt circuit from the return line around the rectifying unit to the source, has the effect of stabilizing the filter operation by minimizing or entirely avoiding the effects of leakage from the filter condensers.

Without this condenser, experience has shown that disturbances, in the nature of a low frequency hum, are impressed upon the plate circuit, interfering with the reception, due to modulation of the rectified current by the alternations of the current from the source.

This shunt circuit, with the condenser 55 between the return line and the source, modifies the condenser action in the filter so as to avoid this source of trouble in the set.

It has been found, in actual practice, that this shunt circuit does not modify the functioning of the set in any way when the source is of a direct current.

By the above arrangement, the anode 16 and its associated cathode 17, and the anode 28 and its associated cathode 29 are connected in series with each other, with the filter and with the translating device, one being upon the input side and the other upon the return side of the translating device, the anode 16 being connected with one terminal of the source and the cathode 29 being connected with the other terminal of said source.

The arrangement of the anode 57 and its associated cathode 58 and the anode 61 and its associated cathode 15 is the same as that heretofore described in relation to the other rectifying units, the anode 57 being connected through the line 14 with one terminal of the source, and the cathode 15 being connected through the line 4 with the other terminal of the source.

The arrangement above described affords two alternative paths for the flow of current having positive polarity, and this is true whether the source is an alternating or a direct current, and rectifiers in one of these paths restricts the flow of the current of positive polarity to the other path. Irrespective of the path through which the positive current may be flowing, such current is impressed through the line 18 upon the filter and the translating device. Both paths are constantly closed, so that the rectifying unit action is fully automatic, whether the source be of alternating or direct current.

One of the electronic rectifiers, connected with one branch line, forms a normally closed path to the line 18, and the other electronic rectifier connected with said branch prevents any current flow across the line. The same condition is true as to the electronic rectifiers on the other side of the line.

In this manner, I am enabled to impress upon the filter and the translating device, whatever its nature, a uni-directional current of positive polarity, since the various electronic rectifiers have a substantially constant impedance. This ensures the delivery of a current, the potential of which is constant excepting for variations which may occur in the potential of the source.

In the arrangement shown in Fig. 1, therefore, means are provided controlling and limiting the direction of flow of the current to one of two paths, alternatively, according to the reversals in the current flow in the source, in the case of alternating current, or according to the polarity of the connection with the source in a direct current, and also rectifying means functioning as such only when the device is used with alternating current.

In the embodiment of the invention shown in Fig. 1, each of these means consists of rectifying units as described.

The translating device, including the member 20, consists of an antenna 30, line 31, condenser 32, line 33, inductance coil 34, condenser 36 and

ground connection 35. A line 38—42 between the inductance 34 and a grid 43 of a vacuum tube has therein a grid condenser 40 and a grid leak 41, the anode 49 and the cathode 44 of said tube. The line 39 is connected with the condenser 36, inductance 34 and tuning condenser 37 and with the return line 25 through the line 24, which is also connected with the condensers 62 and 63.

The input to the translating device is through the line 45 between the filter and the member 20, the other side of this member 20 being connected through the line 21 with the anode 22 of the vacuum tube provided with the heater 10, this tube having a cathode 23 and a grid 52 connected with the anode 49 by the line 51—48 containing therein the condenser 50. Connecting the line 45 with the line 48 is a line 46 having therein a resistor 47, and connected across the line 51—24, between the condenser 50 and the grid 52, is a resistor 54.

The above details of the translating device, in the form of a radio receiving set, are merely for the purpose of indicating the current flow of the translating device in relation to the device of my invention.

In the embodiment of the invention shown in Fig. 2, the branch line 66 corresponds with the branch line 4 and the branch line 90 corresponds with the branch line 14 shown in Fig. 1. The terminals 64 and 65 correspond with the terminals 2 and 3 of Fig. 1.

One of these branch lines, 66, instead of being connected with the anode of a rectifying unit, is connected with one terminal of a resistor 67. The other branch line 90 is connected with one terminal of a resistor 115. These resistors 67 and 115 control and limit the direction of flow of current from the source, whether this source be alternating or direct current, and correspond in function with those rectifying tubes shown in Fig. 1 having the function of controlling and limiting the direction of flow of the current.

The resistors 67 and 115 are connected with each other and have approximately equal resistance so as to ensure substantially the same voltage drop in the current flowing through each. The remaining terminal of each resistor is connected by the line 68 with an anode 69 of an electronic rectifying unit having a cathode 70 and a heater 86. The cathode 70 is connected through the line 71 with the inductance 72 of a filter having condensers 110 and 113 connected by the lines 109 and 112 with opposite terminals of the inductance, and through the line 111 with the branch line 90. The terminals of the inductance 72 are also connected by the lines 101 and 105 with condensers 102 and 104 connected through the line 103 with the branch line 66. The filter is connected by the line 73 with the member 74 of a radio receiving set or other translating device.

In this embodiment of the invention, the return of the current is through a ground connection at 83 to the source. The heater 86 of a rectifying tube and the heater 88 of a vacuum tube in the translating device are energized by current passing through the line 23, the resistor 85, line 87 and line 89, the line 84 being connected with the branch line 66 and the line 89 being connected with the branch line 90.

The translating device shown in this figure, and also in Fig. 3, consists of an antenna 91 connected through the line 92, condenser 93, line 94, inductance 95 and line 79 to the ground connection 80. The line 94 is connected through

the line 96 with the grid 100, this line having therein a condenser 98 and grid leak 99. The member 74 is connected by the line 75 with the anode 76 of the electronic tube having the heater 88, and the cathode 77 is connected with the line 78 and the line 79. A tuning condenser is connected across the lines 96—78 between the grid leak and the antenna.

Extending from the point of connection of the line 68 to the resistors 67—115 is a line 81—83 having therein a condenser 82. This line is connected with the line 78 and also with the line 73 through the line 106—108 having therein a condenser 107.

In this form of the invention, there will be a reduction of the voltage delivered by the source, as a result of the sum of the impedance of the rectifying tube and of one of the resistors 67—115, but the full voltage of the line, as modified by the resistor 85, will be impressed upon the heaters.

The embodiment of the invention shown in Fig. 3 is identical with the shown in Fig. 2, with the exception that the line 84, instead of being connected with one of the branch lines, as 66, is connected with these branch lines through one or the other resistor 67—115 so as to reduce the voltage of the line supplying energy to the heaters of the rectifying or vacuum tubes.

In the embodiment of the invention shown in Fig. 4, branch lines 118 and 130, plug terminals 116 and 117, and resistors 119 and 131, corresponding in arrangement with those shown in Figs. 2 and 3, are used. An all metallic return line 127—132 is used, one of these lines being connected with the branch line 130 and the other being connected with the branch line 118.

Arranged in one return line is an electronic rectifying tube, the anode 128 of which is connected with the line 127 and the cathode 129 of 40 which is connected with the branch line 130. The other return line 132 is connected with the anode 133 of another electronic rectifying tube, the cathode 134 of which is connected with the branch line 118.

45 The line 120, connected with both resistors 119 and 131, is connected with the inductance 121 of a filter, which in turn is connected by the line 122 with the member 123 of the translating device. Connected across the lines 120 and 127 by means of lines 162 and 164 is a condenser 163. Connected across the lines 122 and 127 by the lines 159 and 161 is a condenser 160, the condensers 160 and 163 forming a part of the filter.

46 The heaters 136 and 138 of the rectifying unit 55 and the heater 140 of the translating device are connected in series by means of a line leading from the branch line 118, having therein a resistor 135.

Like with the arrangement of resistors as shown in Figs. 2 and 3 of the drawings, the voltage of the current in the line 120 will be approximately one-half that of the voltage of the supply from the source. When the operation of the translating device requires higher voltages, I employ 65 a condenser 163 connected across the lines 118 and 120, the alternate charging and discharging of which, when alternating current is used, substantially doubles the voltage delivered to the inductance 121 of the filter.

70 Extending from the line 127 to the branch line 130 is a line 165—167 having therein a condenser 166.

The translating device, including the member 123, is substantially identical with that shown in Figs. 2 and 3, with the exception that an all

metallic return line is used instead of a ground return.

This device consists of an antenna 142 connected by the line 143 and, through the condenser 144, line 145, inductance 146, line 147, condenser 148 and line 149, to the ground connection 150. The antenna is connected with the grid 158 of an electronic tube through the line 151, condenser 155 and line 151, which line is provided with the usual grid leak 156.

Across the lines 121 and 151 is the usual tuning condenser 153, the plates of which are connected with said lines by the lines 152 and 154 respectively. The anode or plate 125 is connected by a line 124 with the member 123, and the cathode 126 is connected with the return line 127.

The radio set shown in this figure is not provided with a condenser corresponding with the condenser 107 in Figs. 2 and 3.

Referring to Fig. 5 of the drawings, this embodiment of the invention includes therein branch lines 166' and 180 connected with terminals 165' and 164' of an ordinary plug. In lieu of electronic rectifying tubes or resistors in controlling and limiting the direction of the flow of the current, I employ two condensers 179 and 190, one of which is connected with the branch 180 and the other of which is connected with the branch 166'. The two condensers are connected by the line 178.

Two electronic rectifying tubes are used in this embodiment of the invention, the anode 167' of one of which is connected with the branch 166', and the anode 210 of the other of which is connected with the branch 180. The former anode is also connected with the condenser 190, and the latter is connected with the condenser 179. The cathodes 168' and 211 of said rectifiers respectively are connected by the lines 169 and 212 and the common line 170 with the inductance 171 of the filter, which filter is connected by the line 172 with a member 173 of the translating device. The return line is shown at 177, one end of this line being connected with ground so as to adapt the device for use with direct current, and the other end of which is connected with the line 178 between the condensers 179 and 190.

Connected across the line 170-177 by the lines 207 and 208 is a condenser 208. Connected across the lines 172 and 177 by the lines 204 and 206 is a condenser 205, these condensers forming a part of the filter structure.

I believe that in this arrangement the condensers 179 and 190, in addition to limiting and controlling the direction of flow of the current, act very much as the condenser 168 shown in Fig. 4, increasing the voltage of the current impressed upon the filter and the translating device, and, unlike the arrangement shown in Fig. 4, will impress additional voltage on the line with both alternations of an alternating current.

The translating device is substantially identical with that shown in Fig. 4, the antenna being shown at 191 and the connections between same and the ground connection 197 consisting of the line 192, condenser 193, line 194, inductance 195 and line 196. The tuning condenser 199, the condenser 200, the grid leak 201 and grid 203 are the same as in Fig. 4. The anode 179 of the electronic tube is connected with the member 173 by the line 174 and the cathode 176 of this tube is connected to the line 177.

The heaters of the rectifying tubes in the rectifying unit and the radio electronic tube are connected in series, one end of the line supplying

current being connected by the line 181 with the branch line 166' and having a resistor 182 therein which is connected by the line 183 with the heater 184, this heater being connected by the line 185 with the heater 186, which in turn is connected by the line 187 with the heater 188. This heater in turn is connected by the line 189 to the branch line 180.

It will be noted that no condenser corresponding with the condenser 148 of Fig. 4 is used in the connection between the inductance 195 and the ground connection 197, this line 196 being used as a return line when the current supply is direct current.

In the embodiment of the invention shown in Fig. 6, the arrangement of parts of "hook-up" is like that shown in Fig. 4, with the exception that no condensers are used to raise the voltage of the current impressed upon the filter. The branch lines 254-255 and 268-299 are respectively connected with the plug terminals 253 and 253 which may be connected with the terminals of either an alternating or a direct current source.

The direction of the current flow is controlled by a rectifying unit containing resistors 256 and 300, and electronic rectifying tubes, one of which has an anode 297 and a cathode 298, and the other of which has an anode 266 and a cathode 267. An electronic rectifying tube is arranged in the return line to each branch line, the cathode of each tube being connected with a branch line. A line 257, connected to the adjacent terminals of the resistors 256-300, leads to the inductance 258 of a filter. The return line 264 of the translating device is connected by branch lines 298 and 265 with the anodes 297 and 266. Filter condensers 277 and 278 are connected across the line 259 from the inductance to the member 260 of the translating device and the return line 264 and across the lines 257 and 264.

The heaters 271 and 273 of the two rectifying tubes and 275 of a vacuum tube or tubes in the translating device are connected in series and are energized by current drawn from a branch line through the line 269 having a resistor 270 therein, and through lines 272 and 274, the heater circuit being completed through the line 276 connected with the other branch line 268.

The translating device, including the member 260, is substantially identical with that shown in Fig. 4, and includes an antenna 279 connected by the line 280 and through the condenser 281, line 282, inductance 283, line 284, condenser 285 and line 286 with ground at 287.

The antenna is connected with the grid 292 of the vacuum tube having the heater 275, through the line 288-291 having therein the condensers 290 and grid leak 289.

Across the line 288-294 is the usual tuning condenser 294, the plates of which are connected with said lines by the lines 293 and 295. The anode or plate 262 of said vacuum tube is connected by the line 291 to the member 260, and the cathode 263 of said tube is connected with the return line 264.

Referring to Fig. 1, it will be observed that A. C. or D. C. enters plug 2, 3, and in the case of D. C. with 3 as positive, current flows from 3 through line 4, resistance 5, filament heater 6, line 7, filament heater 8, line 9, filament heater 10, line 11, filament heater 12, lines 13 and 14, to negative side 2 of supply. At the same time current flows from line 4 through anode or plate 16, to cathode 17, line 18, resistance or choke 19, 70 to translating device 20, also charging condensers

62 and 63, through line 21 and plate 22 to cathode 23, lines 24, 25, 26 and 27, to plate 28, cathode 29 and line 14 to the negative side 2 of the supply, part of the current charging condenser 55.

Wireless waves are intercepted by antenna 30 and are converted into radio frequency currents which pass by line 31 through condenser 32, line 33, inductance coil 34, condenser 36 and then to ground 35. At the same time these currents pass by line 38 to grid condenser 40, grid leak 41, line 42, to grid 43, cathode 44, and by line 39 to condenser 36, and ground 35, some of the current passing from line 38 through condenser 37, line 39, condenser 36, to ground 35.

From the filter choke or resistor, 19, current flows by line 45 to line 46, resistor 47, line 48 to anode or plate 49, cathode 44, and line 24, to lines 25, 26 and 27, anode 28, cathode 29, line 14 to negative side 2 of the supply. Also from line 48 to condenser 50, lines 51, grid 52, line 53, resistor 54 and line 24 and to the negative side of the supply as before stated.

It will be observed that if the plug connection to the power supply is reversed so that connection 2 is at the positive side of the power supply line, current flows through lines 14 and 55, anode 51, cathode 58, lines 59 and 18, to choke or resistor 19, line 45, translating device 20, line 21, anode 22, cathode 23, lines 24, 25, 26, 60 anode 61, cathode 15, and line 4, and to the reversed negative side 3 of the power supply line.

When an alternating current power supply is used the circuits are the same and the effect is the same as if the plug were rapidly changed or reversed in position as aforesaid, and the condensers 62 and 63 are alternately charged and discharged into lines 18, 45 and line 24 respectively.

In Fig. 2, A. C. or D. C. enters plug 64, 65 and in the case of D. C. with 65 as positive, current flows from 65 through line 66, resistor 67, charging condenser 82, line 68, anode 69, cathode 70, line 71, resistor or choke 72, charging condensers 113, 110 and 107, to line 73, translating device 74, line 75, anode 76, cathode 77, lines 78 and 79 to ground, 89. At the same time current flows from line 66 to line 84, to resistor 85, heater 86, line 87, heater 88, line 89, line 90, to the negative side 64 of the power supply.

As illustrated in the radio circuit shown, wireless waves are intercepted by antenna 91, converted into radio frequency currents which pass by line 92 to condenser 93, line 94, inductance 95, line 79, to ground 80, part of the current passing from line 94 to line 96, grid leak 99, and grid condenser 98, to grid 100, cathode 77, lines 78, and 79, and ground 80, some of the current passing from line 96 to condenser 97, lines 78, 79 and ground 80.

It will be observed that if the plug connection is reversed so that connection 64 is at the positive side of the power supply line, current flows through line 90, and resistor 115, to line 68, anode 69, cathode 70, resistor 72, charging condensers 102, 104 and 107, through line 73, translating device 74, line 75, anode 76, cathode 77, and lines 78, 79, to ground 80. Current also flows from line 90 to line 99, heater 88, line 87, heater 86, resistor 85, lines 64 and 66, to the reversed negative side 65 of the line. The flow of radio frequency currents is exactly the same as explained above.

When an alternating current power supply is used, the circuits are the same and the effect is the same as if the plug were rapidly changed or

reversed in position as aforesaid, and condensers 102, 104, 110 and 113 are alternately charged and discharged across lines 73, 70, 111 and 103 respectively, it being assumed that one side of the power supply is grounded.

In the modification shown in Fig. 3, line 84 is connected to the intersection between resistors 67 and 115, instead of being connected to the intersection of lines 66 and 103. As a result a lower voltage is obtainable for the heaters. This circuit permits operation on 220 volts with full wave rectification and other advantages of Fig. 2 and permits the use of standard 110 volt vacuum tubes on 220 volt circuits.

In Fig. 4, A. C. or D. C. enters plug 116, 117, and in the case of D. C. with 117 as positive, flows from 117 to line 118, resistor 119, line 120, resistor or choke 121, charging condensers 160 and 163, to line 122, translating device 123, line 124, anode 125, cathode 126, line 127, anode or plate 128, cathode 129, line 130, to negative side of power supply at 116. Current also flows from line 118 to resistor 135, heater 136, line 137, heater 138, line 139, heater 140, lines 141 and 130, to the negative side of the power supply line at 116. As illustrated in the radio circuit shown, wireless waves are intercepted at antenna 142, and are converted into radio frequency currents which flow through line 143, condenser 144, line 145, inductance 146, line 147, condenser 148, and line 149 to ground 150. Also flowing from line 145 to line 151, line 152, condenser 153, lines 154, 127, 147, condenser 148, line 149, to ground 150, also flowing from line 151, through grid leak 156 and grid condenser 155 to line 157, grid 158, cathode 126, line 127, and thence to ground 150. It will be observed that if the plug connection is reversed so that 116 is on the positive side of the line, current flows from plug 116 to line 130, resistor 131, line 120, to choke or resistor 121, charging condensers 160 and 163, to line 122, translating device 123, line 124, anode 125, cathode 126, lines 127 and 132, anode 133, cathode 134, line 118 and to the reversed negative side 117 of the power supply line. Current also flows from line 130 to line 141, heater 140, line 139, heater 138, line 137, heater 136, to resistor 135, line 118, to the reversed negative 117 of the power supply line.

When an alternating current power supply is used, the circuits are the same and the effect is the same as if the plug were rapidly changed or reversed in position as aforesaid, and the condensers 160 and 163 are alternately charged and discharged. The condenser 163 is charged on every alternate half cycle, and on the other half cycle it is discharged into line 120, thus providing a means when alternating current is used, for increasing voltage as desired.

In Fig. 5, A. C. or D. C. enters plug 164', 165'. In case of D. C. with 165' as positive, it flows from 165' to line 166', anode 167', cathode 168', to lines 169 and 170, to choke or resistor 171, charging condensers 205 and 203, to line 172, translating device 173, line 174, anode 175, cathode 176, lines 177, 196, ground 197 and thence to the grounded side of the power supply line.

As illustrated in this radio circuit, wireless waves are intercepted by antenna 191 and are converted into radio frequency currents which pass by line 192, through condenser 193, line 194, inductance 195, line 196 to ground 197. At the same time these currents pass by line 198 to grid leak 201 and grid condenser 200, to line 202, grid 203, cathode 176, line 177, line 196, ground 197.

They also pass from line 198 through condenser 199 to ground 197.

If the plug connection to the power supply is reversed so that connection 164' is at the positive side of the power supply line, current flows from 164 to line 180, to anode 210, cathode 211, lines 212 and 170, resistor or choke 171, charging condensers 205 and 208, to line 172, translating device 173, line 174, anode 175, cathode 176, and lines 177 and 196, to ground 197 and to the grounded side of the power supply line.

When an alternating current power supply is used, the flow of current on one half cycle is from plug connection 165' to line 166', anode 167', cathode 168', lines 169, 170, resistor or choke 171, line 172, translating device 173, line 174, anode 175, cathode 176, line 177, line 178, condenser 179, and line 180 to the other side of the line through plug connection 164. On the other half of the cycle, current flows from plug connection 164 to line 180, anode 210, cathode 211, line 212, line 170, resistor or choke 171, line 172, translating device 173, line 174, anode 175, cathode 176, line 177, line 178, condenser 199, and line 166', to the other side of the power supply line through plug 165'. Part of the current flowing from line 179 on every alternation, charges condensers 205 and 208. The flow of current from the antenna system is the same as described above.

In Fig. 6 A. C. or D. C. enters plug 252, 253, and in case of D. C. with 253 as positive, current flows from 253 to lines 254 and 255, resistor 256, line 257, choke or resistor 258, charging condensers 277 and 278, line 259, translating device 260, line 261, anode 262, cathode 263, lines 264 and 265, anode 266, cathode 267, and line 268 to the negative side of the plug 252. Current from line 254 also flows to line 269, resistor 270, line 271, heater 271', line 272, heater 273, line 274, heater 275, line 276, and line 268 to negative side of the plug 252.

In the radio portion of the circuit, the radio waves are intercepted by antenna 279 and converted into radio frequency current passing through line 230, condenser 281, line 282, inductance 283, line 284, condenser 285, line 286, to ground 287, part of the current passing from line 282 to line 288, grid leak 289, condenser 290, line 291, grid 292, cathode 263, line 264, line 284, condenser 285, line 286 to ground 287. Part of the current from line 288 also flows to line 293, condenser 294, line 295, lines 264 and 284, condenser 285, line 286, to ground 287.

If the plug connection to the power supply is reversed so that connection 252 is at the positive side of the power supply line, current flows from plug 252 to line 268, to line 299, resistor 300, line 257, resistor or choke 258, line 259, translating device 260, line 261, anode 262, cathode 263, line 264, line 298, anode 297, cathode 296, line 254 to the now negative side 253 of the power supply line. Part of the current flows from line 268 to line 276, heater 275, line 264, heater 273, line 272, heater 271', line 271, resistor 270, to lines 269 and 254, to the now negative side 253 of the power supply line.

When an alternating current power supply is used the circuits are the same and the effect is the same as if the plug were rapidly changed or reversed in position as aforesaid, and condensers 277 and 280 are alternately charged and discharged.

It will be observed that in all forms of the invention herein shown and described, the device

may be used with a source of either alternating or direct current, and that there will be a continuous uni-directional flow of current at a substantially constant potential, irrespective of the polarity of the connection with the source.

5 This is due to the use of a rectifying unit in which two constantly closed paths having substantially equal and constant continuing impedance are provided, each path having therein an electronic rectifying tube limiting the direction of flow of the current, in conjunction with other means, either electronic rectifying tubes or resistors permitting the current to select said paths alternatively, according to the polarity of the connection with the source.

10 Under all conditions, a uni-directional current of positive polarity is impressed upon a filter through a common line, and the output of said filter is impressed upon a translating device, 15 whether this be a radio receiving set, hearing aid or other type of device capable of utilizing the current delivered by the device of my invention.

The various elements in the rectifying unit, to wit: electronic rectifying tubes, resistors and condensers, all have small dimensions and are of 20 light weight so as to permit the construction of a small unit which may be readily incorporated in a structure embodying the filter and the translating device.

25 30 These elements will all operate over long periods of time without any attention from the user, and without any material variance in the potential of the current impressed upon the filter. Furthermore, the working conditions in each path between the source and the filter will remain substantially unchanged in relation to the conditions in the other path.

35 35 Of course, it will be understood that various modifications may be made in the construction and arrangement of circuits and parts without departing from the spirit of invention as claimed.

I claim:

40 45 1. In a device of the character described adapted to be operated from either a direct or an alternating current source, a circuit from said source having therein in series a translating device including therein an anode, a cathode, and a heater, a filter, and means affording two constantly closed paths through which current may 50 alternatively flow, including a thermionic rectifying unit, and two branch lines adapted to be connected respectively with the terminals of said source, whereby a uni-directional current of positive polarity is impressed upon said filter and the anode of said translating device, irrespective of 55 whether said branch lines are connected with an alternating or a direct current source, and irrespective of the polarity of such connection, a heater for said rectifying unit, conductors connecting the heaters in said rectifying unit and in 60 said translating device across said branch lines, and a return line isolated from said last named heater circuit, having a connection with the cathode in said translating device and being of uniform potential from said cathode connection to 65 the source, whereby the heater and the cathode in said translating device are at different potentials.

70 75 2. In a device of the character described adapted to be operated from either a direct or an alternating current source, a circuit from said source having therein in series a translating device including therein an anode, a cathode, and a heater, a filter, and means affording two constantly closed paths through which current may alter-

natively flow, including a thermionic electronic rectifying unit, and two branch lines adapted to be connected respectively with the terminals of said source, whereby a uni-directional current of positive polarity is impressed upon said filter and the anode of said translating device, irrespective of whether said branch lines are connected with an alternating or a direct current source, and irrespective of the polarity of such connection, a heater for said rectifying unit, conductors connecting the heaters in said rectifying unit and in said translating device across said branch lines, and a return line isolated from said last named heater circuit, having a connection with the cathode in said translating device and being of uniform potential from said cathode connection to the source, whereby the heater and the cathode in said translating device are at different potentials.

3. In a device of the character described adapted to be operated from either a direct or an alternating current source, a circuit from said source having therein in series a translating device including therein an anode, a cathode, and a heater, a return line, a filter, and means affording two constantly closed paths through which current may alternatively flow, including two branch lines adapted to be connected respectively with the terminals of said source, two thermionic electronic rectifiers each including therein an anode, a cathode, and means for heating the cathode, the anode of one of which and the cathode of the other of which are connected with the same branch line, and the cathode of one of which is connected with said filter and the anode of the other of which is connected with said return line, and two other thermionic electronic rectifiers each including therein an anode, a cathode, and means for heating the cathode, the anode of one of which and the cathode of the other of which are connected with the other branch line, and the cathode of one of which is connected with the filter and the anode of the other of which is connected with said return line, whereby a uni-directional current of positive polarity is impressed upon said filter and said translating device, irrespective of whether said branch lines are connected with an alternating or a direct current source, and irrespective of the polarity of such connection, and conductors connecting the heaters of said rectifying units and in said translating device across said branch lines, said return line being isolated from said last named heater circuit, having a connection with the cathode in said translating device and being of uniform potential from said cathode connection to the source, whereby the heater and the cathode in said translating device are at different potentials.

4. In a device of the character described adapted to be operated from either a direct or an alternating current source, a circuit from said source having therein in series a translating device including therein an anode, a cathode, and a heater, a return line, a filter, and means affording two constantly closed paths through which current may alternatively flow, including two branch lines adapted to be connected respectively with the terminals of said source, two thermionic electronic rectifiers each including therein an anode, a cathode, and means for heating the cathode, the anode of one of which and the cathode of the other of which are connected with the same branch line, and the cathode of one of which is connected with said filter and the anode of the other of which is connected with said return line,

and two other thermionic electronic rectifiers each including therein an anode, a cathode, and means for heating the cathode, the anode of one of which and the cathode of the other of which are connected with the other branch line, and the cathode of one of which is connected with the filter and the anode of the other of which is connected with said return line, whereby a uni-directional current of positive polarity is impressed upon said filter and said translating device, irrespective of whether said branch lines are connected with an alternating or a direct current source, and irrespective of the polarity of such connection, heaters co-operating with said anodes and said cathodes respectively, a line having a resistor therein from one of said branch lines to said heaters, and a line from said heaters to said other branch line, said return line being isolated from said last named heater circuit, having a connection with the cathode in said translating device and being of uniform potential from said cathode connection to the source, whereby the heater and the cathode in said translating device are at different potentials.

5. In a device of the character described adapted to be operated from either a direct or an alternating current source, a circuit from said source having therein in series a translating device including therein an anode, a cathode, and a heater, a return line, a filter, and means affording two constantly closed paths through which current may alternatively flow, including two branch lines adapted to be connected respectively with the terminals of said source, two thermionic electronic rectifiers each including therein an anode, a cathode, and a heater common to both of said anodes and said cathodes, the anode of one of which and the cathode of the other of which are connected with the same branch line, and the cathode of one of which is connected with said filter and the anode of the other of which is connected with said return line, and two other thermionic electronic rectifiers each including therein an anode, a cathode, and a heater common to both of said anodes and said cathodes, the anode of one of which and the cathode of the other of which are connected with the other branch line, and the cathode of one of which is connected with the filter and the anode of the other of which is connected with said return line, whereby a uni-directional current of positive polarity is impressed upon said filter and said translating device, irrespective of whether said branch lines are connected with an alternating or a direct current source, and irrespective of the polarity of such connection, and conductors connecting the heaters in said rectifying units and in said translating device across said branch lines, said return line being isolated from said last named heater circuit, having a connection with the cathode in said translating device and being of uniform potential from said cathode connection to the source, whereby the heater and the cathode in said translating device are at different potentials.

6. In a device of the character described adapted to be operated from either a direct or an alternating current source, a circuit from said source having therein in series a translating device including therein an anode, a cathode, and a heater, a return line, a filter, and means affording two constantly closed paths through which current may alternatively flow, including two branch lines adapted to be connected respectively with the terminals of said source, two resistors, lines connecting op-

posite terminals of said resistors with said branch lines respectively, a thermionic electronic rectifying unit including therein an anode, a cathode, and a heater, a line connecting the anode thereof with the other terminals of said resistors, a line connecting the cathode thereof with said filter, whereby a uni-directional current of positive polarity is impressed upon said filter and said translating device, irrespective of whether said branch lines are connected with an alternating or a direct current source, and irrespective of the polarity of such connection, and conductors connecting the heaters in said rectifying unit and in said translating device across said branch lines, said return line being isolated from said last named heater circuit, having a connection with the cathode in said translating device and being of uniform potential from said cathode connection to the source, whereby the heater and the cathode in said translating device are at different potentials.

7. In a device of the character described adapted to be operated from either a direct or an alternating current source, a circuit from said source having therein in series a translating device including therein an anode, a cathode, and a heater, a return line, a ground connection for said return line, a filter, and means affording two constantly closed paths through which current may alternatively flow, including two branch lines adapted to be connected respectively with the terminals of said source, two resistors, lines connecting opposite terminals of said resistors with said branch lines respectively, a thermionic electronic rectifying unit including therein an anode, a cathode, and a heater, a line connecting the anode thereof with the other terminals of said resistors, a line connecting the cathode thereof with said filter, whereby a uni-directional current of positive polarity is impressed upon said filter and said translating device, irrespective of whether said branch lines are connected with an alternating or a direct current source, and irrespective of the polarity of such connection, and conductors connecting the heaters in said rectifying unit and in said translating device across said branch lines, said return line being isolated from said last named heater circuit, having a connection with the cathode in said translating device and being of uniform potential from said cathode connection to the source, whereby the heater and the cathode in said translating device are at different potentials, said filter including an inductance, a line adjacent each terminal of said inductance having a condenser therein, one plate of each condenser being connected with one of said branch lines, and a line adjacent each terminal of said inductance having a condenser therein, one plate of which is connected with said other branch line.

8. In a device of the character described adapted to be operated from either a direct or an alternating current source, a circuit from said source having therein in series a translating device including therein an anode, a cathode, and a heater, a return line, a ground connection for said return line, a filter, and means affording two constantly closed paths through which current may alternatively flow, including two branch lines adapted to be connected respectively with the terminals of said source, two resistors, lines connecting opposite terminals of said resistors with said branch lines respectively, a thermionic electronic rectifying unit including therein an anode, a cathode, and a heater, a line connecting the anode thereof

with the other terminals of said resistors, a line connecting the cathode thereof with said filter, whereby a uni-directional current of positive polarity is impressed upon said filter and said translating device, irrespective of whether said branch lines are connected with an alternating or a direct current source, and irrespective of the polarity of such connection, conductors having a resistor therein in series with said heaters, connecting the heaters in said rectifying unit and in said translating device across said branch lines, said return line being isolated from said last named heater circuit, having a connection with the cathode in said translating device and being of uniform potential from said cathode connection to the source, whereby the heater and the cathode in said translating device are at different potentials, said filter including an inductance, a line adjacent each terminal of said inductance having a condenser therein, one plate of each condenser being connected with one of said branch lines, and a line adjacent each terminal of said inductance having a condenser therein, one plate of which is connected with said other branch line.

9. In a device of the character described adapted to be operated from either a direct or an alternating current source, a circuit from said source having therein in series a translating device including therein an anode, a cathode, and a heater, a filter, and means affording two constantly closed paths through which current may alternatively flow, including two branch lines adapted to be connected respectively with the terminals of said source, two resistors, lines connecting opposite terminals of said resistors with said branch lines respectively, two thermionic electronic rectifying units each including therein an anode, a cathode, and a heater, lines connecting the cathodes thereof with the opposite terminals of said resistors, a line connecting the anodes thereof, a return line connected with the anodes of said rectifying units respectively, a line connecting the other terminals of said resistors with said filter, whereby a uni-directional current of positive polarity is impressed upon said filter and said translating device, irrespective of whether said branch lines are connected with an alternating or a direct current source, and irrespective of the polarity of such connection, and conductors connecting the heaters in said rectifying units and in said translating device across said branch lines, said return line being isolated from said last named heater circuit, having a connection with the cathode in said translating device and being of uniform potential from said cathode connection to the source, whereby the heater and the cathode in said translating device are at different potentials.

10. In a device of the character described adapted to be operated from either a direct or an alternating current source, a circuit from said source having therein in series a translating device, including therein an anode, a cathode, and a heater, a filter, and means affording two constantly closed paths through which current may alternatively flow, including two branch lines adapted to be connected respectively with the terminals of said source, two resistors, lines connecting opposite terminals of said resistors with said branch lines respectively, two thermionic electronic rectifying units each including therein an anode, a cathode, and a heater, lines connecting the cathodes thereof with the opposite terminals of said resistors, a line connecting the

anodes thereof, a return line connected with the anodes of said rectifying units respectively, a line connecting the other terminals of said resistors with said filter, whereby a uni-directional current of positive polarity is impressed upon said filter and said translating device, irrespective of whether said branch lines are connected with an alternating or a direct current source, and irrespective of the polarity of such connection, a condenser connected across the line to said filter and conductors connecting the heaters in said rectifying units and in said translating device across said branch lines, said return line being isolated from said last named heater circuit, having a connection with the cathode in said translating device and being of uniform potential from said cathode connection to the source, whereby the heater and the cathode in said translating device are at different potentials.

11. In a device of the character described adapted to be operated from either a direct or an alternating current source, a circuit from said source having therein in series a translating device including therein an anode, a cathode, and a heater, a filter, and means affording two constantly closed paths through which current may alternatively flow, including two branch lines adapted to be connected respectively with the terminals of said source, two resistors, lines connecting opposite terminals of said resistors with said branch lines respectively, two thermionic electronic rectifying units each including therein an anode, a cathode, and a heater, lines connecting the cathodes thereof with the opposite terminals of said resistors, a line connecting the anodes thereof, a return line connected with the anodes of said rectifying units respectively, a line connecting the other terminals of said resistors with said filter, whereby a uni-directional current of positive polarity is impressed upon said filter and said translating device, irrespective of whether said branch lines are connected with an alternating or a direct current source, and irrespective of the polarity of such connec-

tion, a condenser connected across the line to said filter and one of said branch lines, and conductors having a resistor therein connecting the heaters in said rectifying units and in said translating device across said branch lines, said return line being isolated from said last named heater circuit, having a connection with the cathode in said translating device and being of uniform potential from said cathode connection to the source, whereby the heater and the cathode in said translating device are at different potentials.

12. In a device of the character described adapted to be operated from either a direct or an alternating current source, a circuit from said source having therein in series a translating device including therein an anode, a cathode and a heater, a filter, and means affording two constantly closed paths through which current may alternatively flow, including a thermionic electronic rectifying unit and two branch lines adapted to be connected respectively with the terminals of said source, whereby a uni-directional current of positive polarity is impressed upon said filter and the anode of said translating device, irrespective of whether said branch lines are connected with an alternating or a direct current source, and irrespective of the polarity of such connection, a heater for said rectifying unit, conductors connecting the heaters in said rectifying unit and in said translating device across said branch lines, a return line isolated from said last named heater circuit, having a connection with the cathode in said translating device and being of uniform potential from said cathode connection to the source, whereby the heater and the cathode in said translating device are at different potentials, and means for completing the signal circuit around said rectifying unit, including therein a conductor connected with the return line and with the source of the signal circuit, and a condenser in the length of said conductor.

HARRY G. CISIN.
